US0D1102317S

(12) **United States Design Patent** (10) **Patent No.:** **US D1,102,317 S**
(45) **Date of Patent:** **** Nov. 18, 2025**

(54) **FLORAL ARRANGING DEVICE**

(71) Applicant: **Floracraft Corporation**, Ludington, MI (US)

(72) Inventors: **Lindsey Dellinger**, Grand Rapids, MI (US); **Dondi Richardson**, Ludington, MI (US); **Amy Steidl Olson**, Ludington, MI (US); **Eric Erwin**, Ludington, MI (US); **Brett Kincaid**, Grand Rapids, MI (US); **Daniel Tagtow**, Ludington, MI (US)

(73) Assignee: **Floracraft Corporation**, Ludington, MI (US)

(**) Term: **15 Years**

(21) Appl. No.: **29/905,275**

(22) Filed: **Oct. 18, 2023**

(51) **LOC (15) Cl.** **11-02**

(52) **U.S. Cl.** **D11/146**; D11/152; D11/153; D99/18; D99/19

(58) **Field of Classification Search**

(57) **CLAIM**

The ornamental design for a floral arranging device as shown and described.

DESCRIPTION

FIG. 1 is a perspective view a floral arranging device showing our design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

It being understood that the dashed lines throughout the drawings do not form part of the claimed invention.

1 Claim, 6 Drawing Sheets
